A. LILIANSTROM

PLAYER PIANO ACTION

Filed March 8, 1920

Fig. 1.

Fig. 2.

Inventor:

Alfred Lilianstrom,
By his son Alfred Lilianstrom,
Attest,

UNITED STATES PATENT OFFICE.

ALFRED LILIANSTROM, OF CHICAGO, ILLINOIS.

PLAYER-PIANO ACTION.

Application filed March 8, 1920. Serial No. 364,066.

To all whom it may concern:

Be it known that I, ALFRED LILIANSTROM, a citizen of the United States, residing at Chicago, in the county of Cook and State 5 of Illinois, have invented a new and useful Improvement in Player-Piano Actions, of which the following is a specification.

This invention relates to pneumatic player piano actions and particularly to those having sections arranged in tiers.

An object of this invention is to provide a section which is simple and easy to manufacture, in which the number of parts is reduced to a minimum and which is strong 15 and durable, when assembled.

These and other objects are accomplished by my invention which is fully described in the following specification as shown in the accompanying drawing, in which—

20 Figure 1 is a transverse vertical section thru one of the player action sections on the line 1—1 of Fig. 2; and Fig. 2 is a partial plan view of a tier of sections which constitutes a valve chest.

25 The section is made up of a horizontal member 10, to which are secured in side by side relation a series of narrow blocks 11, each of which forms the base of a striker pneumatic having a movable member 12 hingedly 30 connected at 13 to the base, the base 11 and movable member 12 being connected by a flexible bellows 14. The movable member of the pneumatic is connected to the regular piano action in any suitable manner, as by

35 means of a rod 15 which is adjustably connected to a bracket 16 on the sticker 17, which is pivotally connected to the wippen 18 by means of the pin 19. These latter elements are well known and may be mounted 40 in the piano action in any well known manner.

Each horizontal member 10 extends substantially the length of the key-board, not shown, and is carried by the piano player 45 in any suitable manner. This member is preferably made of a single integral piece of wood and has a suction chamber 20, which is cut therefrom for substantially its entire length. This chamber is covered by 50 a plate 21, which is preferably glued or screwed thereto, so as to be practically airtight. The ends of the chamber are closed, and a passage 22 leads from one end of the chamber to the bellows, not shown, or other 55 means for producing a vacuum.

A series of chambers 23 are formed longitudinally of the members, such chambers having a central opening extending completely thru the members and surrounded by a circular valve seat 24. A corresponding valve seat 25 is threaded and screwed in thru the upper part of the chamber 23, and has an opening 26 through which the chamber 23 communicates with the atmosphere. A doubled faced valve 27 having a stem 27^a 60 rests normally upon the lower valve seat 24, thereby closing it. The chamber 23 communicates at all times with the interior of the striker pneumatic 14 thru the passage 28 in the member 10 and the passage 29 in the 70 base 11 of the striker pneumatic.

Immediately under the chamber 23 is formed a chamber 30 which is preferably made by removing material from both the under side of the horizontal member 10 and the upper side of the base 11 of the pneumatic. A flexible diaphragm 31 is secured in this chamber and has a button 32 at its center, which is immediately beneath the guide 27^a of the valve 27, when the diaphragm 31 is at its lowest point. The part of the chamber 30 lying above the diaphragm communicates with the long suction chamber 20 thru the passage 33, while that part of the chamber 30 lying below the 85 diaphragm communicates thru the passage 34 and the tube 35 with the tracker board, not shown, in any well known manner.

A recess 36 is formed in the edge of the member 10 and corresponds with each 90 passage 34 and communicates therewith through a passage 37. The outer end of the recess 36 is closed by means of a screw 38, while the inner end communicates with the suction chamber 20 thru a passage 39 which 95 is partly closed by bleeder valve 40 having a very fine hole 41, therein.

The method of operation of my device is as follows: The various parts are normally in the position shown and as soon as the 100 bellows or other suction means is started, the suction chamber 20 is maintained under a partial vacuum. This assumes, of course, that there is a note-sheet covering that particular opening in the tracker board, which 105 is connected to the tube 35. As soon, however, as an opening in the note sheet registers with this particular opening in the tracker board air is admitted to the tube 35 thru the passage 34 raising the diaphragm 110

31 and the valve 27. This closes communication between the chamber 23 and the atmosphere thru the passage 26, and opens communication of the striker pneumatic 14, 5 with the chamber 23, which is now connected to the valve seat 24, the upper part of the chamber 30 in the passage 33 with the suction chest 20. The result is that the striker pneumatic 14 immediately collapses 10 raising the sticker 17 and the wippen 18 causing the corresponding piano string to be struck by the hammer in a well known manner.

As soon as the opening in the note-sheet 15 passes and the corresponding opening of the tracker board is again closed, the pressure in the passage 34 leaks thru the bleeder valve 41 so as to keep the pressure therein substantially equal to that in the suction 20 chest 20. The result is that the valve 27 is returned to the position shown and the air rushes in thru the passages 26 and 28 to the striker pneumatic 14, which resumes the position shown, thereby returning the parts 25 of the piano action to their normal position.

While I have shown and described but a single embodiment of my invention, it is to be understood that it is capable of many modifications. Changes, therefore, in the 30 construction and arrangement may be made which do not depart from the spirit and scope of my invention as disclosed in the appended claims, in which it is my intention to cover all novelty inherent in the device

as broadly as possible, in view of the prior 35 art.

What I claim as new and desire to secure by Letters Patent is:—

1. In a playerpiano action, a tier of a sectional valve chest comprising an integral 40 member having a longitudinal groove extending substantially the length thereof, an imperforate cover for said groove, two opposed aligned valve seats in said member, a chamber therebetween, a valve movable to 45 engage either of said seats, a striker pneumatic having a stationary block secured to the under side of said integral member and communicating with said chamber, and a diaphragm sunk into said block and operably connected to said valve.

2. In a playerpiano action, a tier of a sectional valve chest comprising an integral member having a longitudinal groove extending substantially the length thereof, an imperforate cover for said groove, two opposed aligned valve seats in said member, a chamber therebetween, a valve movable to engage either of said seats, a striker pneumatic having a stationary block secured to 60 the under side of said integral member and communicating with said chamber, a diaphragm sunk into said block and operably connected to said valve, and a passage with in said block connecting the lower side of 65 said diaphragm with the tube leading to the tracker board.

ALFRED LILIANSTROM.
